UNITED STATES PATENT OFFICE.

ALBERT E. THORNLEY, OF PAWTUCKET, RHODE ISLAND, ASSIGNOR TO NARRAGANSETT MACHINE COMPANY, OF PAWTUCKET, RHODE ISLAND, A CORPORATION OF RHODE ISLAND.

GYMNASIUM APPARATUS.

1,094,823.

Specification of Letters Patent. Patented Apr. 28, 1914.

Application filed March 25, 1913. Serial No. 756,660.

To all whom it may concern:

Be it known that I, ALBERT E. THORNLEY, a citizen of the United States, residing at Pawtucket, in the county of Providence 5 and State of Rhode Island, have invented a new and useful Improvement in Gymnasium Apparatus, of which the following is a specification.

This invention relates to certain new and 10 useful improvements in gymnasium apparatus, and pertains more particularly to vaulting horses.

The primary object of the invention is to provide a device of the type set forth in 15 which either end of the horse may be raised or lowered independently of the other end thereof, to allow one end to lie in a horizontal plane above the other end, or to permit one end to be first moved to the desired 20 horizontal elevation and then the other end to be moved to the same elevation.

In the drawings: Figure 1 is a vertical sectional view of an apparatus embodying the present invention. Fig. 2 is an enlarged 25 vertical fragmentary sectional view of one of the supporting columns. Fig. 3 is a fragmentary side elevation of one of the supporting columns showing the latch thereon, and Fig. 4 is a similar view showing the latch in full lines and the spring in dotted lines.

The horse 1 has rigidly secured to its under side a pair of depending brackets 2. The hollow columns 3 may have their lower 35 ends attached to a suitable base, or seated in sockets in the floor of the gymnasium or otherwise firmly supported. Tubular posts 4 slide on the interiors of the columns 3 and are formed with a series of spaced holes 5. The upper end of one of the posts 4 is pivotally attached at 6 to one of the brackets 2, while the other bracket is connected by 40 means of a link 7 to the other post 4. Each of the columns 3 has a long leaf spring 8 attached thereto, the lower ends of the springs being secured to the columns by 45 means of screws 9 or any other suitable fastening means. The upper ends of the springs 8 have pins 10 rigidly secured thereto, which pins project through openings provided therefor in the columns 3 and into one of the holes 5 of the tubular posts 4 in order to support the posts at the desired elevation.

For the purpose of actuating the upper

free ends of the springs 8 in order to move the pins 10 out of the holes 5, latches 11 are employed, the latter having pins 14 which underlie the upper free ends of the springs 8 and are pivotally secured at 12 to bosses 30 13 formed on the columns 3. The handle portions of the latches extend outwardly from the springs 8 in order to allow same to be easily gripped by the fingers of the operator.

In operation the lower or handle portion of one latch is moved outwardly, thus causing the pin 14 at the upper end of the latch to move the free end of the spring 8 outwardly, thereby causing the pin 10 to move 70 out of the hole 5, whereupon the end of the horse is then moved to the desired position, after which the latch is moved inwardly permitting the pin to again enter one of the holes 5 in the post 4, thus locking said end 75 of the horse in position. The same operation is then performed at the opposite end of the horse to bring the latter into horizontal or inclined position, as desired.

Having thus described my invention, I 80 claim as new and desire to secure by Letters Patent;—

1. In a device of the type set forth, a pair of hollow columns, tubular posts sliding in the columns and having a series of spaced holes therein, a horse pivotally connected to one post, a link connection between the horse and the other post, leaf springs secured at their lower ends to the columns and having pins at their upper ends for engagement in the holes of the posts, and latches for actuating the free ends of the springs to move the pins outwardly from the holes of the posts, the latches being pivoted to the columns and having pins disposed beneath 85 the springs, the lower ends of the latches extending outwardly from the springs.

2. In a device of the type set forth, a pair of hollow columns, tubular posts sliding in the columns and having a series of spaced 100 holes therein, a horse pivotally connected to one post, a link connection between the horse and the other post, leaf springs secured at their lower ends to the columns and having pins at their upper ends for engagement in the holes of the posts, and latches for actuating the free ends of the springs to move the pins outwardly from the holes of the posts.

3. In a device of the type set forth, hollow 105 columns, posts sliding in the columns and

having a series of spaced holes therein, spring means carried by the columns to engage in said holes to support the posts at varying heights, means to operate the spring means, a horse, and means connecting each post to the horse whereby either end of the horse may be raised or lowered independent of the other end by raising or lowering of the posts.

10 4. In combination with columns, posts slidingly related to the columns, a horse, means connecting each post to the horse whereby either end of the horse may be raised or lowered independent of the other end by sliding movement of the posts, and locking means for independently locking each post to its column.

15 5. In combination with a horse and means for pivotally supporting each end of the horse, means for adjustably and independently supporting each of said first named means to allow the horse to be moved to assume horizontal or inclined position.

20 6. In combination with a horse, a support for each end thereof, and means whereby either end of the horse can be raised or low-

ered independent of the other end of the horse.

7. In combination with a horse, and vertically movable posts, means connecting each post to the horse whereby either end of the horse may be raised or lowered independent of the other end by vertical movements of the posts, and means for adjustably supporting each post.

35 8. In combination with a horse and a vertically movable post for each end of the horse, means connecting each post to the horse whereby either end of the horse may be raised or lowered independent of the other end by vertical movements of the posts, means to movably support each post, means to lock the posts in varying vertical positions, and means to actuate the locking means.

40 45 In testimony whereof I have signed my name to this specification in the presence of two subscribing witnesses.

ALBERT E. THORNLEY.
